UNITED STATES PATENT OFFICE.

JULIUS H. KINTZELE, OF ST. LOUIS, MISSOURI, ASSIGNOR TO THE BISHOP & BARCOCK COMPANY, OF CLEVELAND, OHIO, A CORPORATION OF OHIO.

BOTTLE-FILLING MACHINE.

1,098,449.

Specification of Letters Patent. Patented June 2, 1914.

Application filed January 7, 1910. Serial No. 536,797.

To all whom it may concern:

Be it known that I, JULIUS H. KINTZELE, a citizen of the United States, and a resident of St. Louis, State of Missouri, have 5 invented a new and useful Improvement in Bottle-Filling Machines, of which the following is a specification, the principle of the invention being herein explained and the best mode in which I have contemplated applying that principle, so as to distinguish it 10 from other inventions.

The present invention, relating as indicated to bottle filling machines, has more particular regard to that class of such machines wherein the bottle to be filled is alternately raised and lowered upon a vertically reciprocable bottle lift carried by a rotatable frame.

The object of the invention is the improvement of the mechanism for actuating such reciprocable bottle lifts in machines of this class, and such invention is, hence, obviously not concerned with any details of the filling mechanism, proper, including the filling tank, filling valve, and associated parts.

One preferred construction of bottle lift device quite generally employed in connection with multiple filling machines of the kind in question, comprises a series of levers in the form of bell cranks that are carried by a rotating structure in which are mounted the bottle lifts proper. The outer ends of said bell cranks are connected with such lifts either directly or by suitable connecting rods, while their inner ends, which are generally shorter than such outer ends, bear against a relatively fixed cam having a conformation such that, as any particular lever 40 is carried around by the rotation of the machine, it is caused to oscillate so as to raise the bottle lift, and then to lower the same, the filled bottle being taken off and an empty one put on while such lift is lowered, and 45 the filling operation taking place while the bottle is raised.

The special object of the present invention is the provision of means whereby the friction between the levers and the fixed cam, which is obviously very considerable in machines of any size, despite the introduction of rollers or other anti-friction devices, may be almost entirely eliminated.

To the accomplishment of this and related objects, said invention, then, consists

of the means hereinafter fully described and particularly pointed out in the claims.

The annexed drawings and the following description set forth in detail certain mechanism embodying the invention, such disclosed means constituting, however, but one of various mechanical forms in which the principle of the invention may be used.

In said annexed drawings:—Figure 1 is partly a side elevation and partly a vertical section of a typical bottle filling machine wherein have been incorporated one approved form of my present improvements; Fig. 2 is a corresponding sectional view of a portion of such machine illustrating the improved details in a different operative position; Fig. 3 is a plan view of the improvements in question; Fig. 4 is a view similar to Fig. 3, but showing a modification as to one detail; Fig. 5 is a view on a larger scale, of a catch forming a feature of such improvements; Figs. 6 and 7 respectively illustrate various modified forms of such catch; and Fig. 8 shows the adaptation of the invention to another type of machine from that shown in Fig. 1.

Referring, first of all, to the form of machine illustrated in Figs. 1, 2 and 3, only so much of the general structural features of the machine will be here noted as will be 85 helpful to an understanding of the improvements constituting the present invention. Such typical machine, then, comprises a suitable base A formed with a central, vertically rising portion a in which is rotatably held a tubular shaft B. This shaft carries the frame of the machine which consists of a series of branching arms b on the upper ends of which is supported the filling tank B' which here takes the form of an annular chamber. The liquid to be filled into the bottles is supplied to this chamber through a supply pipe b' that extends within the base A and thence passes upwardly through the tubular shaft B and has 100 branches b² connecting with said chamber. Pressure fluid is also supplied to said chamber through a suitable intermediate chamber or drum B² provided with regulating apparatus for maintaining the liquid within 105 the annular filling chamber at a proper level, and under proper pressure, for the filling operation, as will be readily understood.

The filling valves b³ illustrated are of the reciprocable type, such valves being mount- 110

ed in the bottom of the annular chamber and being rendered operative by the bringing up of bottles against the same from below, while the lowering of said bottles leaves the valves again inoperative or closed. These valves likewise form no part of the present invention, and as there are various other well known constructions equally adaptable for use in connection with machines of this sort, the details thereof do not require to be further described.

The rotatable parts of the machine, which comprise tubular shaft B and the parts just referred to as being supported thereby, as also the bottle lifts C presently to be described, are given their proper rotative movement about the axis of the machine, by means of a worm b^4 in the base A that drives a worm wheel b^5 fixedly secured on the lower end of said shaft B.

The lifts C which serve to raise and lower the bottles relatively to the filling valves b^3 are provided directly below and in line with the respective filling valves, and comprise in effect simply reciprocable plungers that are carried in the radially extending arms c of a spider C' keyed, or otherwise non-rotatably secured to shaft B. Such spider and the bottle lifts thus carried thereby of course rotate with the general frame of the machine as though an integral part therewith so that the lifts and valves always remain in such alinement. Each plunger C at its upper end is provided with a platform or shelf c' adapted to receive and hold a bottle of the particular size being filled, which shelf may, if desired, be resiliently supported upon the plunger proper. Reciprocation of the plungers is derived, as has been previously indicated, from a cam, designated D, Fig. 1, through a series of bell-cranks or levers D' of which one is obviously required for each plunger. Said cam, the form of which is better shown in Fig. 3, is fixedly secured to the upwardly extending portion a of the machine base and has its contacting face so disposed as to always bear squarely against the short arms d of the bell-cranks as the latter are oscillated in the course of the travel of the frame around the axis of the machine. A connecting rod d^2 preferably joins the outer or long arm D' of each crank with the corresponding plunger. In certain types of machine such connection is made direct. Such long arms of the cranks are extended in my present improved construction, a short distance beyond the point of attachment of the connecting rods therewith, and, attached to each plunger supporting arm c so as to lie adjacent to the position occupied by such crank arm in its upper position, is a depending bracket E in which is mounted a catch e normally held by a flat spring e' or by gravity, in position to engage the projecting portion d^3 of the bell

crank arm and prevent the same from dropping. When thus held, the cam is obviously not needed and its bearing face is hence cut away throughout substantially all that portion of its circumference that corresponds with the raised position of a bottle lift (see Fig. 3). When, however, the recessed portion d^4 of the cam, corresponding with the lowered position of the lift, is reached, in the course of travel of the lever about the same, the catch requires to be withdrawn, and to this end, I provide a trip e^2 conveniently mounting the same on the upper end of a standard E' that is secured to the machine base. The position of this trip relatively to the cam D is shown in the figure last referred to, from a reference to which figure it will be seen that as any particular bottle lift is brought around adjacent thereto, the lower depending end of the catch e is engaged by the cam face of the trip e^2 , and the catch e' on the catch's inner face, which engages with the projecting portion of the lever, is withdrawn from such engagement. The lower end of the catch, which is engaged by the trip, furthermore, bears a roller e^3 in order to reduce friction. Preferably the main actuating cam D is formed so as to engage with the short arm of a bell crank just before the catch e is thus engaged by the trip to release the outer end of such bell crank, such engagement relieving the catch of any weight and permitting its easy withdrawal. The short arm d of the bell crank now encounters the recessed portion of the cam, and as it travels in along the same, the outer arm d' together with the bottle lift C is lowered. As such short arm travels out again, however, the bottle lift is raised into its upper position and the catch now being past the trip e^2 again becomes effective and engages and holds the lever, together with the plunger, from dropping. As a result of the foregoing construction, it will be obvious that frictional contact between the bell-cranks and the main actuating cam occurs only during the relatively short time that the latter is utilized in lowering and raising the plungers constituting the bottle lifts. During the entire remaining portion of their travel, no contact with the cam is required and as a matter of fact, such cam may be entirely cut away throughout all but the portion just referred to, so as to assume the form shown in Fig. 4.

It will be obvious that my improved device for relieving the friction involved in having the bell-cranks contact with the main actuating cam throughout the whole course of their travel, is equally adaptable to that form of the machine in which such bell cranks are directly connected with the plunger, as also to the earlier type of filling machine in which the lifts are directly raised and lowered by the operation of a

cam track that contacts with their lower ends. This latter form of machine with my improvements incorporated, is illustrated in Fig. 8, where the plungers C^2 of the bottle lifts, it will be seen terminate in rollers c^2 that are adapted to run along a circular cam track D^2 suitably disposed to engage therewith. This cam track instead of extending entirely around the machine, however, consists only of the portions required to raise and lower the lifts, such lifts being held in their upper position during the remainder of their course of travel by catches e^{13} operating in exactly the same fashion as just described and released by a trip e^{14} stationed adjacent to the point where the lowering of the lifts is designed to commence.

It has been indicated above that in place of a spring for rendering the catches operative gravity operated means may be substituted; thus for example a counter-weight e^3 integral with a pivoted catch e^4 is shown in Fig. 7. The catch e^4 in this case depends below its pivotal axis, just as does catch e in the form previously described, and so requires to be oscillated in the same direction. The trip e^5 here provided (shown in dotted outline only) is accordingly disposed to engage the counterweight from below. A variant form of spring catch is also illustrated in Fig. 7, where the catch assumes the form of a radially reciprocable plunger e^6 , normally retained in its inner operative position by a spring e^{10} , while a depending projection e^{11} on its rear end both serves as a stop for such plunger and as means whereby the trip may engage therewith, as will be readily understood.

Other modes of applying the principle of my invention may be employed instead of the one explained, change being made as regards the mechanism herein disclosed, provided the means stated by any one of the following claims or the equivalent of such stated means be employed.

I therefore particularly point out and distinctly claim as my invention:

1. In a machine of the class described, the combination with a rotatable frame, filling devices borne thereby, and lifts for bringing the packages to be filled into operative relation with said devices; of a series of bell-cranks connected with said lifts; a relatively stationary cam adapted to engage successive bell-cranks upon rotation of said frame to raise the corresponding lifts; means respectively co-operative with said lifts to retain the same in such raised position; and relatively stationary means adapted to successively withdraw said retaining means directly from their retaining positions.

2. In a machine of the class described, the combination with a rotatable frame,

filling devices borne thereby, and lifts for bringing the packages to be filled into operative relation with said devices; of a series of bell-cranks connected with said lifts; a relatively stationary cam adapted to engage successive bell-cranks upon rotation of said frame to raise the corresponding lifts; catches respectively co-operative with said lifts to retain the same in such raised position; and a relatively stationary trip adapted to successively withdraw said catches directly from their retaining positions.

3. In a machine of the class described, the combination with a rotatable frame, filling devices borne thereby, and lifts for bringing the packages to be filled into operative relation with said devices; of a series of bell-cranks connected with said lifts; a relatively stationary cam adapted to engage successive bell-cranks upon rotation of said frame to raise the corresponding lifts; catches respectively co-operative with said lifts to retain the same in such raised position; means normally rendering said catches thus operative; and a relatively stationary trip adapted to successively withdraw said catches directly from their retaining positions.

4. In a machine of the class described, the combination with a rotatable frame, filling devices borne thereby, and lifts for bringing the packages to be filled into operative relation with said devices; of a series of bell-cranks connected with said lifts; a relatively stationary cam adapted to engage successive bell-cranks upon rotation of said frame to raise the corresponding lifts; catches respectively co-operative with said lifts to retain the same in such raised position; springs normally rendering said catches thus operative; and a relatively stationary trip adapted to successively withdraw said catches directly from their retaining positions.

5. In a machine of the class described, the combination with a rotatable frame, filling devices borne thereby, and lifts for bringing the packages to be filled into operative relation with said devices; of a series of bell-cranks connected with said lifts; a relatively stationary cam adapted to engage successive bell-cranks upon rotation of said frame to raise the corresponding lifts; means respectively co-operative with said lifts to retain the same in such raised position; relatively stationary means adapted to successively withdraw said retaining means directly from their retaining positions, and a cam adapted to engage the corresponding bell-crank just prior to the operation of said last-named means to control the lowering of the corresponding lift.

6. In a rotary bottle filling machine, mechanism for lifting the bottle to filling position comprising an angle lever having a long

arm and a short arm and a cam to engage the short arm of said lever and operate the same, and a latch to engage the long arm of said lever when the bottle has reached filling position to sustain said mechanism while the bottle is being filled.

7. In a rotary bottle filling machine, mechanism for lifting the bottle to filling position comprising a bottle rest, an angle lever having a long arm and a short arm, a link engaged with said long arm to operate said bottle rest, a cam adapted to engage the short arm of said lever and operate the same and a finger on the long arm projecting outward from its engagement with said link, and a latch to engage said finger when the bottle has reached filling position to sustain said mechanism while the bottle is being filled.

8. In a rotary bottle filling machine, mechanism for lifting and sustaining a bottle in filling position and for lowering the bottle after it is filled, comprising an angle lever having a long arm and a short arm, a bottle rest carried by the long arm of said lever, a cam to engage the short arm of said lever and operate the same and having a high point which carries the lifting mechanism to filling position, a latch to engage the long arm of said lever when the bottle has reached filling position to sustain said mechanism while the bottle is being filled, a tripper device for moving said latch to inoperative position so that the filling mechanism may

lower the bottle after it is filled, said cam having another high point to lift the mechanism above the latch and enable the tripper to swing the latch out of engagement with said mechanism.

9. In a rotary bottle filling machine, mechanism for lifting and sustaining a bottle in filling position and for lowering the bottle after it is filled, comprising an angle lever having a short arm and a long arm terminating in a finger, a link operatively engaged with said long arm, a bottle rest, a yielding connection between the link and the bottle rest, a latch to engage said finger and sustain said mechanism while the bottle is being filled, a cam to engage the short arm of said lever and operate the same and having a high point to lift the mechanism above the latch so that the latch may be engaged with the finger, a tripper device for moving said latch to inoperative position so that said mechanism may lower the bottle after it is filled, said cam having another high point to lift the lever relatively to the bottle rest and above the latch so that the latch can be swung out of operative engagement with said finger.

Signed by me this 31st day of December, 1909.

JULIUS H. KINTZELE.
